UNITED STATES PATENT OFFICE.

LORENZIO JOHNSON, OF LOUISVILLE, KENTUCKY, ASSIGNOR OF ONE-HALF
TO A. A. CHAPMAN, OF LOUISVILLE, KENTUCKY.

MUSICAL INSTRUMENT.

SPECIFICATION forming part of Letters Patent No. 738,811, dated September 15, 1903.

Application filed January 10, 1903. Serial No. 138,512. (No model.)

To all whom it may concern:

Be it known that I, LORENZIO JOHNSON, a citizen of the United States, residing at Louisville, in the county of Jefferson and State of Kentucky, have invented a new and useful Musical Instrument, of which the following is a specification.

My invention relates to improvements in stringed musical instruments; and the objects of my improvement are, first, mellowness and sweetness of tone; second, strength of tone, and, third, symmetry. I attain these objects by the construction illustrated in the accompanying drawings, in which—

15 Figure 2 is a face view of the instrument; Fig. 1, a central longitudinal section; Fig. 3, a plan view of the neck and supporting-bar, and Fig. 4 a transverse section through the body on the line 20 21.

20 Similar reference-numerals refer to similar parts throughout the several views of the drawings.

The body 1 of my new musical instrument is of the conventional heart shape, terminating at its lower end in two gracefully-formed lobes, with a longitudinal depression on the back between the lobes, thus forming, practically, two cotyledonal lobes, of which the sound-board forms the flat portion. The 25 sound-board 2 is flat and of relatively large area in order to produce a full tone. To thoroughly support the sound-board 2 to mellow the tone and to communicate the vibrations to the entire body, I provide what I call a 30 "sound-bar" 5, which is secured transversely to the under side of the sound-board 2, and a supporting-bar 3, which is an extension of and integral with the neck 7 and head 4, on which the said sound-bar 5 rests. The bar 3 35 extends through the entire body and is relatively broad vertically to prevent its bending and consequent sagging of the neck 7 and finger-board 11. The tailpiece 10 is attached to the lower end of the bar 3 to relieve the body 40 of the instrument of all strain from the strings. The bridge 6 is preferably of the form used on violins. A sound-hole 8 in the sound-board

2 is located in the most effective place under the strings and between the finger-board 11 and the bridge 6. The strings 9 are preferably of wire and applied in pairs, as on the mandolin, and similarly tuned and played with a plectrum.

I have found by experiment that the back of my instrument having the two cup-shaped 55 depressions due to the cotyledonal form reflects the sound-waves against the flat sound-board in such a way that the instrument produces a sweet, mellow, and yet full and strong tone peculiar to it which I have not been able 60 to obtain from any other shape. The external globular protrusions on the back, leaving the longitudinal depression between the cotyledons, make this instrument more easy to hold while playing than the mandolin and 65 others, preventing the familiar and annoying slipping and sliding out of position.

I am aware that other musical instruments, as guitars, have a bar to strengthen the sound-board and others also, as banjos, have an extension of the neck through the body. I do not, therefore, claim these devices broadly; but

What I claim as my invention, and desire to secure by Letters Patent, is—

75 1. In a stringed musical instrument, the combination of a body, a sound-board on said body, a sound-bar secured transversely to the under surface of said sound-board, and a longitudinal supporting-bar extending through 80 said body, integral with the neck of the instrument, on which said sound-bar rests, substantially as specified.

2. As a new article of manufacture, a musical instrument, having its body of the conventional heart shape, consisting of two symmetrical, cotyledonal lobes, and a sound-board forming the flat portion of said cotyledonal lobes, substantially as and for the purpose specified.

85 3. In a stringed musical instrument, the combination of a body having two symmetrical lobes, a sound-board of the conventional heart shape, providing relatively extended

area, a sound-bar secured transversely to the under side of said sound-board, and a supporting-bar extending throughout the body integral with the neck of the instrument and 5 adapted to support the said sound-bar and communicate the vibrations to the entire body, all these parts coacting to produce

strong, mellow and true tone, substantially as specified.

LORENZIO JOHNSON.
